UNITED STATES PATENT OFFICE.

FRANK A. SMITH, OF NAUGATUCK, CONNECTICUT.

FUEL VAPORIZER AND MIXER.

Application filed December 6, 1922. Serial No. 605,145.

The invention relates to improvements in devices for mixing with air a fluid combustible intended for use with internal combustion engines; and it has for its object a device of this character which will be of simple and rugged construction and insure, for example, complete vaporization of a liquid fuel and effect a thorough mixture of same with air. A further object of the invention consists in an arrangement whereby this mixture may be preheated. The invention has for a still further object to dispense with the usual type of carburetor which includes a spray or jet device, or the like, for vaporizing the fuel.

In accordance with the invention, the fuel and air supplied to the engine are caused to travel a helical path thru a suitable mixing chamber; and, if desired the mixture therein may be heated to the desired degree and the air preheated, as by employing the exhaust gases from the engine for this purpose. The liquid fuel may be supplied thereto in any suitable manner; but it is preferred to also provide a member affording a large surface as in providing a helical path for the liquid fuel, the path being of sufficient length to insure complete vaporization of the fuel in its travel thru the chamber.

The nature of the invention, however, will best be understood when described in connection with the accompanying drawings, in which—

Fig. 1 is a view of an internal combustion engine and manifold, showing the improved vaporizer connected thereto.

Fig. 2 is a similar view illustrating the application thereto of a preheater for the mixture.

Fig. 3 is an enlarged longitudinal section of a vaporizer of the type shown in the embodiment illustrated in Fig. 2.

Similar characters of reference designate corresponding parts thruout the several views.

Referring to the drawings, 10 designates a suitable casing, for example cylindrical in shape, in which the air and fuel are to be suitably mixed and vaporized. One end of this cylinder is provided with an outlet duct 11 designed to be connected to the inlet mani-

fold 12 of the internal combustion engine. A throttle valve 13 is included in said outlet duct and is operated in the usual manner to control the supply of the mixture from the cylinder 10 to the engine.

At the opposite end, cylinder 10 is provided with an inlet duct 14 for air; and the same is preferably arranged to be preheated. For this purpose, there is provided over the exhaust manifold 15 of the engine a pipe or stove 16, open at the one end and connected at the other end with the inlet duct 14. Air is drawn in thru the pipe 16 as the engine is operated, and is thus heated by the exhaust gases therefrom in the exhaust manifold and enters the cylinder 10 in this condition. A combustible fuel as a liquid fuel may be fed in any suitable manner thru a supply pipe 17 to the said cylinder 10, thru a suitable inlet or needle valve 18, having manual control means readily accessible as is well understood.

In Figs. 2 and 3, an arrangement is disclosed wherein the air is similarly preheated but the exhaust pipe 15, also, is arranged to pass axially thru the cylinder 10 and thus serves to heat the mixture within the cylinder.

In order to effect a complete mixture of the liquid fuel and air supplied to the cylinder 10, the mixture is caused to travel a helical path thru the cylinder, dividing walls 20 being provided to this end thru the cylinder in helical arrangement; and, in the embodiment illustrated in Figs. 2 and 3, the same are formed about the axially located exhaust pipe 15 of the engine. These walls 20 completely cover the distance between the pipe 15 and the cylinder wall so that inflowing air is constrained to travel in a helical path thru the said cylinder. This affords a considerable surface for exposure of the liquid fuel to the inflowing air so that, by time the two reach the outlet duct 11, a complete mixture of same will have taken place. The walls 20, also, are preferably of twisted sheet metal but may be of various other constructions, as will be apparent to those skilled in the art; and the mixture may or may not be preheated as set forth, and directly or indirectly from the

exhaust pipe of the engine. Thus, the cylinder 10 may be placed against the engine exhaust or within or about same.

It is preferred, moreover, to force the liquid fuel to similarly take an elongated and tortuous path thru the cylinder and to provide a considerable surface for its vaporization. To this end, the liquid fuel, which may be fed by gravity, pressure or vacuum in the usual manner, is introduced to the cylinder 10 thru the suitably controlled needle valve 18, and is directed to the axis of the said cylinder by a tube 21. Within the tube is provided a ribbon 22 of twisted metal which extends therefrom and is carried along and wound over the exhaust pipe 15, following the convolutions of the helical walls 20 so that the liquid fuel travels along said band and likewise helically toward the outlet duct. This tendency of the fuel to cling to the ribbon of twisted metal is probably due to surface adhesion and the action of the moving column of air thru the passageway, as well as to the fact that the weight of liquid per unit of surface is continuously decreasing as the fuel advances along the ribbon, the liquid finally completely disappearing therefrom when vaporized. Moreover, the ribbon 22 is so placed as to be in contact with the hot exhaust pipe 15, which further serves to effect vaporization of the fuel passing over the band.

It will be understood that the proper proportions of air and liquid fuel will be supplied and maintained in the usual manner by suitable and well-known devices which form no part of the present invention, which relates solely to the novel form of vaporizer and mixer hereinbefore described. The same comprises essentially a casing for receiving air and liquid fuel thru which a mixture thereof is caused to flow in a helical path, the air being preheated, if desirable, as may also be the entire mixture, and the heat being obtained directly or indirectly for this purpose from the exhaust gases of the engine to be supplied with and operated by the gaseous mixture.

I claim:—

1. A vaporizer for liquid fuel for internal combustion engines, comprising a tubular casing forming a chamber and having inlets at one end respectively for air and fuel and an outlet at the other end for a mixture thereof, a helical member disposed in said chamber between the inlet and the outlet thereof to provide with the casing and thruout its entire length a helical passageway of continuous and smooth surface to insure against pocketing thereby of any fuel, said passageway being adapted to direct the air therethru in a whirling movement and to effect a mixture of the same with the fuel, the inlet for the fuel being on the engine side of the inlet for the air and both air and

fuel passing thru the vaporizer in the same direction, means to direct the fuel in liquid form into the said passageway substantially in the longitudinal axis thereof, and a band of metal substantially in the longitudinal axis of the helical member and following its convolutions and adapted to receive said fuel.

2. A vaporizer for liquid fuel for internal combustion engines, comprising a tubular casing forming a chamber and having inlets at one end respectively for air and fuel and an outlet at the other end for a mixture thereof, a helical member disposed in said chamber between the inlet and the outlet thereof to provide with the casing and thruout its entire length a helical passageway of continuous and smooth surface to insure against pocketing thereby of any fuel, said passageway being adapted to direct the air therethru in a whirling movement and to effect a mixture of the same with the fuel, the inlet for the fuel being on the engine side of the inlet for the air and both air and fuel passing thru the vaporizer in the same direction, and a band of metal extending into the fuel inlet to act as a guide for the fuel from the said fuel inlet substantially centrally of the convolutions of the helical member.

3. A vaporizer for liquid fuel for internal combustion engines, comprising a tubular casing forming a chamber and having inlets at one end respectively for air and fuel and an outlet at the other end for a mixture thereof, a helical member disposed in said chamber between the inlet and the outlet thereof to provide with the casing and thruout its entire length a helical passageway of continuous and smooth surface to insure against pocketing thereby of any fuel, said passageway being adapted to direct the air therethru in a whirling movement and to effect a mixture of the same with the fuel, the inlet for the fuel being on the engine side of the inlet for the air and both air and fuel passing thru the vaporizer in the same direction, a tube passing axially thru the casing and helical member to receive the exhaust from the engine, and a band of metal twisted about said axial tube, following the convolutions of the helical member and adapted to receive the said fuel.

4. A vaporizer for liquid fuel for internal combustion engines, comprising a tubular casing forming a chamber and having inlets at one end respectively for air and fuel and an outlet at the other end for a mixture thereof, a helical member disposed in said chamber between the inlet and the outlet thereof to provide within the casing and thruout its entire length a helical passageway of continuous and smooth surface to insure against pocketing thereby of any fuel, said passageway being adapted to di-

rect the air therethru with a whirling movement and effecting a mixture of the same with the fuel, the inlet for said fuel being on the engine side of the inlet for the air and both air and fuel passing thru the vaporizer in the same direction, and a tube extending into the tubular casing from the fuel inlet substantially to the axis of the helical

passageway to act as a guide for the fuel from the said inlet to the convolutions of ¹⁰ the said helical member.

Signed at Naugatuck, in the county of New Haven, and State of Connecticut, this 27th day of November, A. D. 1922.

FRANK A. SMITH.
